UNITED STATES PATENT OFFICE.

LAMECH HARLOW, OF VANCOUVER, CANADA.

TEMPERATURE-INDICATOR AND AUTOMATIC FIRE-EXTINGUISHER FOR DRYING-KILNS AND THE LIKE.

No. 820,571.

Specification of Letters Patent.

Patented May 15, 1906.

Application filed June 30, 1904. Serial No. 214,748.

To all whom it may concern:

Be it known that I, LAMECH HARLOW, of the city of Vancouver, Province of British Columbia, Canada, have invented certain new and useful Improvements in Temperature-Indicators and Automatic Fire-Extinguishers for Drying-Kilns and the Like, of which the following is a specification.

The object of my invention is to devise a simple and effective temperature-indicator and automatic fire-extinguisher for use in drying-kilns or other places where artificial heat is used for drying purposes; and it consists, essentially, of a fine wire fixed at one end, carried back and forth through the kiln, and weighted at its free end or otherwise maintained taut, alarm mechanism and sprinkler mechanism being suitably arranged to be set in operation by the expansion of the wire under the influence of undue heat, substantially as hereinafter more specifically described and then definitely claimed.

Figure 1 is a sectional elevation of the operating parts of my invention. Fig. 2 is a plan view showing the method of wiring the kiln and the arrangement of the sprinklers.

Referring particularly to Fig. 2, A represents a drying-chamber such as used in lumber-drying kilns, laundries, and other places where artificial heat is used for drying purposes. This chamber is provided with sprinklers B, fed by means of the distributing-pipe C. A pipe D connects this distributing-pipe with the water-main. (See Fig. 1.) In this pipe D is located a differential valve E.

The small disk a of the valve controls the water-supply through the pipe D, and the larger disk d operates in a chamber connected by the pipe F with the pipe D between the valve and the main. A valve c is provided in the pipe F, by means of which the passage of the water through the pipe may be controlled. Connected with the chamber of the differential valve is a pipe G, and in this pipe is located a valve H, the stem of which is controlled by the lever I, pivoted on the valve-mounting. The lower end of this lever is engaged with the detent J, pivoted on the pipe G or other suitable stationary part.

It is obvious that by releasing the detent J the valve H would be allowed to open, and thus reduce the pressure in the chamber of the differential valve, which opens and permits the flow of water to the sprinkler system.

The closing of the differential valve is of course effected by closing the valve H, when

the greater pressure on the larger disk d will gradually close the valve. As the disks a and d open and close with water-pressure against their operative faces, the opening and closing of the valve is effected without shock.

To permit of the sprinkler system being operated by hand from any convenient part, I provide a pipe K, communicating with the chamber of the differential valve, preferably by being connected with the pipe G between the valve H and the differential valve. A valve e' is placed in this pipe at any suitable location, so that the pressure in the chamber of the differential valve may be vented at any time desired. The main feature of my invention, however, lies in the means employed for automatically releasing the detent J and for sounding an alarm, as hereinafter described. For this purpose I employ a wire L, preferably of brass or other non-corrodible metal. This wire is fixed at one end and is carried back and forth through the chamber of the kiln around sheaves e.

The free end of the wire is brought up around a sheave f (see Figs. 1 and 2) up to and over a sheave g and has a weight M secured to its end. On this weight is secured a collar n, vertically adjustable on the weight by means of a set-screw h. This collar is normally above the detent J and in position to engage it if the weight be lowered.

From the construction described it follows that if the chamber of the kiln becomes unduly heated the wire will expand, thus dropping the weight M and causing the collar n to contact with and release the detent J. This operates the sprinkler system, as hereinbefore described.

As it is desirable to sound an alarm, I provide the weight M with a second collar O, vertically adjustable on the weight by means of a set-screw i. This collar is in position to engage a detent P as the weight falls. This detent is pivoted on a suitable stationary part, preferably the pipe Q, connected with a suitable source of steam-supply. This pipe contains a valve R, the stem of which is controlled by the lever S, pivoted on the mounting of the valve and having its lower end engaged by the detent. Thus when the detent is caused to fall by contact with the collar O the valve R will be opened and steam allowed to pass through the pipe Q to the whistle j, sounding an alarm as long as the steam-supply lasts.

A distant signal may be given by connect-

ing electric wires *k* and *l*, respectively, to the letent *P* and a suitable insulated contact-piece *m*. These wires will be in circuit with a battery *T* and an electric bell situated at some station where it is desired that the alarm shall be given.

As the collar *O* is vertically adjustable, it may be set to give an alarm before the temperature in the kiln has quite reached the danger-point, so that steps may be taken to reduce the temperature without permitting the sprinklers to flood the kiln.

In order that the general temperature of the kiln may be ascertained at any time, I provide a scale *U*, suitably formed on or connected to some stationary part outside the kiln.

To the wire *L*, I connect at a suitable point the indicator-wire *V*. This wire is carried over suitable sheaves *n' o* and has a weight *p* secured to its end. This weight keeps a suitable tension on the indicator-wire, and its point serves as an index to the scale.

From this construction it is apparent that the degree of expansion of the wiring in the kiln will be indicated by the point of the weight *p*, and thus the average temperature of the kiln readily ascertained by consulting the scale.

I do not desire to limit myself to the exact construction of the details set out, as other methods of wiring the kiln and carrying out the details of the mechanism might be employed which would still fall within the scope of my invention.

The advantages of my device are obvious, as all danger from fire will be eliminated. The system, it will be seen, gives a visible indication of the temperature of the kiln, gives an automatic warning of any dangerous increase in temperature, and in case of the outbreak of fire will instantly flood the kiln from the sprinklers. Further, in case of a local fire, not sufficiently expanding the wire to operate the sprinklers, the valve in the pipe *K* affords an opportunity for the sprinkler system to be put in operation by hand.

What I claim as my invention is—

1. In a fire-extinguisher, a wire fixed at one end and carried through the area to be protected; a sheave over which the wire passes; and a weight secured to the end of the wire, in combination with a sprinkler mechanism; controlling means therefor, adapted to be operated by the said weight when the latter is

lowered by the expansion of the wire under the influence of undue heat; an indicator-wire connected with the main wire; means for tensioning the said wire; an index carried by the indicator-wire; and a scale suitably supported adjacent to the index, substantially as described.

2. In a fire-extinguisher, a wire fixed at one end and carried through the area to be protected; a sheave over which the wire passes; a weight secured to the end of the wire; a vertically-adjustable contact-piece carried by the weight, in combination with a sprinkler mechanism; controlling means therefor, adapted to be operated by the said contact-piece when the latter is lowered by the expansion of the wire under the influence of undue heat; an indicator-wire connected with the main wire; means for tensioning the said wire; an index carried by the indicator-wire; and a scale suitably supported adjacent to the index, substantially as described.

3. In a fire-extinguisher, a sprinkler system located within the area to be protected; a supply-pipe for the sprinkler system; a differential valve therein having connected valve-disks of different areas, the smaller disk controlling the water-supply and the larger fitting a chamber connected behind the disk with the supply-pipe at the inlet side of the valve; a pipe communicating with said chamber behind the larger disk; a valve in said pipe; means operated by a rise of temperature in the kiln for opening the said valve; a second pipe communicating with the said chamber behind the disk; and a controlling-valve in said pipe, substantially as described.

4. In a fire-extinguishing apparatus, the combination of a discharge-pipe normally empty of liquid, and provided with a plurality of sprinkler-orifices; a valve controlling the flow through said pipe to all the sprinkler-orifices; a wire stretched in proximity to the sprinkler-orifices; and means whereby the expansion of the wire by heat opens said valve and permits the flow of fluid to all the sprinkler-orifices, substantially as described.

Signed at Vancouver, in the Province of British Columbia, Canada, this 22d day of June, A. D. 1904.

L. HARLOW.
